UNITED STATES PATENT OFFICE.

IRVIN F. HEPLER, OF NARBERTH, PENNSYLVANIA, ASSIGNOR TO JOHN S. WORTH AND WILLIAM P. WORTH, OF COATESVILLE, PENNSYLVANIA.

GAS-VALVE.

1,097,432.

Specification of Letters Patent.

Patented May 19, 1914.

Application filed February 15, 1913. Serial No. 748,575.

To all whom it may concern:

Be it known that I, IRVIN F. HEPLER, a citizen of the United States, residing in Narberth, county of Montgomery, State of Pennsylvania, have invented certain Improvements in Gas-Valves, of which the following is a specification.

The object of my invention is to construct a simple and effective gas valve which is closed by liquid, said liquid also acting as a dust collector due to the fact that the gas must pass over the surface of the same in flowing through the valve.

In the accompanying drawings:—Figure 1, is a sectional view of my improved gas valve with the water raised sufficiently to seal the valve; Fig. 2, is a similar view, showing the water lowered to a depth to allow the gas to escape from one flue to another; Fig. 3, is a view of a modification of the invention; and Fig. 4, is a diagrammatic view illustrating the location of the valve in connection with furnaces and gas stoves.

Referring to the drawings, A is the casing of the valve made of sheet metal and having a lining of fire brick or other suitable material, which is supported by a flanged ring in the present instance. Below this ring is a water section A', which has a conical bottom α terminating in an outlet which communicates with the pipe F. In this pipe is a suitable valve f which is opened when it is desired to discharge the water from the bottom of the casing.

C is a horizontal gas flue lined with fire brick and communicating with the body portion of the casing A, while B is another horizontal gas flue which terminates in an elbow B' having a flange b by which it is secured to the casing. The end of this elbow extends into the water chamber of the valve, as shown. The elbow is less in diameter than the casing A and the area of the two is such that, when the valve is open, the gas will flow freely, without obstruction, from one flue to the other. The elbow B' is supported at its lower end by one or more braces e , set in brackets a' on the casing of the section A'.

h is a gage for indicating the level of the water in the valve, and g is a trap communicating with the upper portion of the sec-

tion A' and with a pipe G coupled to the outlet pipe F below the valve f .

g' is a sight flow section in the pipe G to enable the operator to readily set the flow of water through the pipe G, when necessary.

E is the inlet pipe for water, in which is a suitable valve by which the flow of water can be controlled.

a^2 is a manhole opening in the upper end of the casing A.

Referring to Fig. 4, the gas valve A is preferably placed in a central position between the two sets of gas stoves D, D' and the flues C and B are connected to the several gas stoves and furnaces H, H' through the gas washers I, I' and dust catchers J, J' in the ordinary manner, so that when both furnaces are in proper condition and are supplying the proper quantity of gas to the stoves, then the valve A is closed, but if one of the furnaces is not working properly and is not supplying the normal amount of gas to the stoves, then the valve is opened by lowering the water in the valve and a given amount of gas is allowed to flow from one flue to the other, so as to supply the stoves with the proper quantity of gas.

In Fig. 3, I have shown a modification of my improved valve, in which the elbow is dispensed with and a straight flue is substituted for it. The flue C' connects with the side of the casing A² and the flue B² connects with the top of the casing and has an extension b³, slightly conical, which terminates within the water section A' of the valve. A³ is a manhole opening, closed by a suitable cover. The other parts of the valve are similar to those described in connection with Figs. 1 and 2.

I claim:—

1. The combination in a gas valve, of a casing having a conical bottom section forming the water chamber; a discharge pipe communicating with the bottom of the conical section at the apex thereof; a valve in said pipe; two flues, one flue communicating with the casing and the other flue having an extension within the casing terminating at the water line so that the water will close the extension or, when it is below the extension, will catch any impurities which may pass into the valve from either flue; a

trapped overflow pipe communicating with the casing above the normal water line and with the discharge pipe below the valve; a lining for the casing above the water line; and a lining for each flue.

2. The combination of a casing having a cylindrical section and a conical bottom section forming a water chamber whereby the surface of the water extends to the full diameter of the casing; a discharge pipe at the apex of the conical section; a valve in said discharge pipe; an inlet water pipe communicating with the casing above the water line; a flue communicating with one side of the casing; and a flue having a right angled neck located within the casing of a diameter considerably less than the casing, the end of the neck extending to a point so that the water can either close the opening in the neck or will catch any impurities which may pass into the valve from either flue when it is below the end of the neck.

3. The combination in a gas valve, of a

casing having a conical bottom forming a water chamber; a valved discharge pipe 25 communicating with the apex of the conical bottom; an inlet pipe for water communicating with the casing above the water line; a trapped overflow pipe communicating with the discharge pipe below the valve and 30 with the body of the casing above the normal water line; two flues, one flue communicating with the casing, the other flue having a right angled neck located within the casing and considerably less in diameter than 35 the said casing, the lower portion of the neck extending to a point within the water chamber; a lining for the casing above the water line; and a lining for each flue.

In testimony whereof, I have signed my 40 name to this specification, in the presence of two subscribing witnesses.

IRVIN F. HEPLER.
